UNITED STATES PATENT OFFICE.

LEWIS M. KEIZER, OF BALTIMORE, MARYLAND, ASSIGNOR TO THE UNION PAPER BAG MACHINE COMPANY, OF PHILADELPHIA, PENNSYLVANIA, A CORPORATION OF PENNSYLVANIA.

PAPER-BAG MACHINE.

SPECIFICATION forming part of Letters Patent No. 687,430, dated November 26, 1901.

Application filed June 12, 1900. Serial No. 20,036. (No model.)

To all whom it may concern:

Be it known that I, LEWIS M. KEIZER, a citizen of the United States of America, residing in the city of Baltimore, in the State of Maryland, have invented certain new and useful Improvements in Paper-Bag Machines, of which the following is a true and exact description, reference being had to the accompanying drawings, which form a part thereof.

10 My invention relates to paper-bag machinery adapted to open and form a bottom upon tucked tubular blanks, the object of my invention being, primarily, to provide a machine on which the whole operation of forming the bottom on the blanks can be carried on by devices moving in such a way and with such slowness of operation that the paper is folded with considerable deliberation and absence from sudden jerks, while the folding

15 devices are also moved in such a way and with such deliberation as to avoid sudden jars and reversals tending to injure the machine; and my invention consists, generally speaking, in the hereinafter-described mechanism comprising a multiple series of traveling folding-beds, each provided with independent mechanism for acting on the tubular blanks to form bottoms upon them, and also in various special devices and details of construction in

20 themselves new and particularly pointed out in the claims.

Reference being now had to the drawings, in which my invention is illustrated in what I believe to be its best and most convenient form, Figure 1 is an end view of the tucked tubular blank such as I use in my machine; Fig. 2, a side view thereof; Fig. 3, an end view showing the end of the tube partly distended; Fig. 4, a side view of the tube in the condition shown in Fig. 3, showing it gripped intermediate of its ends by a pair of rolls. Fig. 5 shows an end view of the tube still farther distended, Fig. 6 being a side view showing the tube grasped by the defining-plates G. G. Fig. 7 is an end view of the tube with its end spread into the box form, Fig. 8 being a side view of the tube in the same condition. Fig. 9 is an end view of the tube with its end spread into a diamond fold, Fig. 10 being a side view

of the tube in the same condition. Fig. 11 is an end view of the tube with its end fully folded into a bag-bottom. Fig. 12 is a side view of the tube in the same condition shown in Fig. 11, and Fig. 13 is a side view of the tube with the bottom folded down as it is for shipment. Fig. 14 is a sectional elevation of my machine, taken as on the central section-line 14 14 of Fig. 16. Fig. 15 is a sectional elevation taken as on the section-line 15 15 of Fig. 16. Fig. 16 is a horizontal section taken as on the section-line 16 16 of Fig. 14. Fig. 17 is an enlarged view in elevation of the device for moving the guiding-finger which directs the tubular blank into the folding-beds of the machine. Fig. 18 is a view showing the relative position of the blank-feed rolls and deflecting-finger at the beginning of the operation of feeding a blank to a folding-bed. Fig. 19 shows the same parts in a later stage of the folding operation, Fig. 20 again showing the same parts in the later stage in the feeding operation when the blank is engaged by the take-in rolls of the bed. Fig. 21 is again a view showing the same parts in a somewhat later stage, and Fig. 22 shows the position of the blank at the time when it is gripped by the bottom-fold-defining plates to be hereinafter described. Fig. 23 is a plan view showing one of the folding-beds and the mechanism connected therewith. Fig. 24 is an elevation of the folding-bed mechanism, shown as on the section-line 24 24 of Fig. 23. Fig. 25 is a front elevation of the folding-bed mechanism. Fig. 26 is an end view of the folding-bed mechanism, shown as taken on the section-line 26 26 of Fig. 24. Fig. 27 is a similar view taken on the section-line 27 27 of Fig. 24. Fig. 28 is a similar view taken on the section-line 28 28 of Fig. 24. Fig. 29 is a similar view taken on the section-line 29 29 of Fig. 24. Fig. 30 is an enlarged plan view of the distending-fingers and immediately-connected mechanism as shown in Fig. 23. Fig. 31 is an enlarged sectional view of the take-in rolls and their immediate connection, shown as taken on the section-line 31 31 of Fig. 24. Fig. 32 is an enlarged sectional elevation of details of construction shown also in Fig. 24. Figs. 33, 34, and 35,

taken consecutively, constitute a diagrammatic illustration of the various operative devices acting on the bag-blank and the means employed for consecutively bringing it into 5 operation. Fig. 36 is an elevation showing the application to my machine of a supplemental device having the function of distending the box into which the end of the tube is spread during the process of forming the bottom. Fig. 37 is a plan view of the same mechanism. Fig. 38 is a view showing in elevation the position of the distending device when it enters the box form. Fig. 39 is a view of the distending device taken as on 10 the section-line 39 39 of Fig. 40. Fig. 40 is a view of the distending device taken on the section-line 40 40 of Fig. 39. Fig. 41 is a perspective view of the blank having the box form open at its end. Fig. 42 is a view in 15 elevation, showing the application of another supplemental device to my machine, having the function of opening or distending the mouth of the tube. Fig. 43 is an end view of the machine having this appliance viewed 20 from the right-hand side of Fig. 42. Fig. 44 is an enlarged view of the distending-plate and the devices for operating it as shown in Fig. 42. Fig. 45 is an end view of the distending-plate with its spindle and parts connected therewith, showing the position of the plate in the mouth of the tube. Fig. 46 shows the operation of the distending-plate upon 25 the tube. Fig. 47 shows a modification of the devices shown in Fig. 30 for spreading 30 the mouth of the tube into a box form, the spreading-fingers being represented in the positions they occupy in entering the tucks of the bottom. Fig. 48 is a plan view of the 35 same device and in the same position as in Fig. 47. Fig. 49 shows the operation of the device in spreading the end of the top of the tube, and Fig. 50 is a side sectional elevation showing a modification of the general construction of my machine.

45 In the drawings, A indicates the tucked tubular blank, A' indicating the side tucks, A² the cross-fold on which the blank is opened in forming the bottom, A³ A³ the side folds, and A⁴ the end folds, formed in extending the 40 mouth of the blank into a box form.

50 A⁵ A⁵, &c., indicate the oblique folds formed in collapsing the box into a diamond fold and forming the triangular flaps of the diamond, which are folded inward to complete 55 the bottom of the bag, as shown in Fig. 11.

B, Figs. 14, 15, and 16, indicates the frame supporting the feed-rolls, deflecting-finger, and actuating devices connected therewith.

B' B' indicate the frame of the machine 60 proper supporting the two preferably circular-sided plates, (indicated at B² B²), these plates being braced together by rods, &c., as indicated at B³ and B⁴, and having the central shaft-bearing, (indicated at B⁵ B⁵), in which 65 rests shaft C of the machine, having attached to one end the gear-wheel C', (see Fig. 16,) engaged with a gear-wheel C², driven by a gear

C³ on a shaft C⁴, to which a driving-pulley C⁵ is attached. On the shaft C⁴ is also secured the gear-wheel C⁶, engaged with and driving the gear C⁷, which in turn drives the gear-wheel C⁸, secured on the shaft C⁹, which shaft directly drives the lower feed-rolls D³, and through a system of gear-wheels (indicated at C¹⁰) the upper feed-roll D⁴ and the two parallel feed-rolls D' D². The shaft C⁹ has also secured to it the cam C¹¹, (see Figs. 16 and 17,) which acts on a cam-roller c¹¹, (see Fig. 17,) attached to a pivoted segment D⁶, which segment (see also Fig. 20) is pivoted on a standard D⁵ and operates through a gear d⁶ on shaft d⁸, to which is attached and by which is oscillated the deflecting-finger D⁸. At D I have indicated the housing for the feed-rolls already mentioned, the rolls D³ and D⁴, 70 acting on the blank only through their segmental portions d³ d⁴, which engage the tube and act upon it at the same time that the take-in rolls H h are also acting upon it, and have the function of stretching the tube taut 75 before it is engaged by the defining-plates G G. E E are plates secured to and rotating with the shaft C. The function of these plates is, primarily, to support the folding-beds, (indicated at F', &c.,) and their peripheries are 80 divided into plane facets, such as are indicated at E', and to which the supports F of the folding-beds are bolted, as shown in Fig. 29, these facets being interspaced with notches, as indicated at E² and E³, to afford 85 clearance for certain parts of the mechanism attached to the folding-beds. As shown in the drawings, (see especially Fig. 29,) the folding-beds are connected with plates E E through the castings F F, which support the 90 ends of a transversely-extending plate or casting F', upon the outer ends of which are in turn supported castings F² F², the three castings forming the frame of the folding-bed and being made in separate parts merely for convenience. The castings F support at one end 95 shaft-bearings, as indicated at F⁴. They have also on their under sides pivoted supporting-lugs, (indicated at F⁵), and in the rear of these lugs an extension having formed in it a shaft-bearing F⁶ and above it a slot, as shown at F⁷. These castings have also in their upper faces 100 guide-slots, as indicated at F⁸. (See Figs. 24, 26, and 29.) The transversely-extending casting or plate F' has formed in its sides and at each end the guiding-grooves, indicated at F⁹. (See Figs. 25, 27, and 29.) The casting is also formed with a central flared opening, as indicated at F¹¹, on each side of which are formed the openings F¹⁰ F¹⁰, (see Figs. 23, 24, 105 and 32,) having guides, as indicated at f¹⁰, formed around their upper edges. Depending from the lower sides of the castings F' and, as shown, secured to the castings by bolts f¹² (see Fig. 32) are the brackets F¹², supporting 110 the shaft-bearings F¹³, from which extend lateral arms F¹⁴, (see Figs. 25, 26, and 28,) having a pivoted bearing at their outer ends, the brackets F¹² supporting also near their up-

per ends shaft-bearings, as indicated at F^{15} . The castings F^2 have formed in their upper portions the guiding-grooves, (indicated at F^{16}), and they are also provided (see Figs. 23 and 26) with laterally-projecting arms supporting guide-bearings, as indicated at $F^{17} F^{17}$.

$F^{18} F^{18}$, &c., indicate brackets secured to and extending laterally from the center of the casting F' . As shown in Figs. 25, 26, 27, and 28, they support on their lower projections the shaft-bearings F^{19} .

Passing now to the mechanism connected with the folding-beds $G G$ (see Figs. 23, 24, and 28) are folding defining-plates pivotally supported at the bottom of the aperture F^{11} on the shafts $G' G'$. When open, they occupy the position shown in Figs. 28 and 20, and when closed the position shown in Fig. 22. The shafts G' (see Figs. 27 and 32) have also attached to them the lever-arms $G^2 G^2$, connected through links G^3 with the lever-arms $G^4 G^4$, secured on the shafts $G^5 g^5$, on which are also supported the take-in rollers, (shown at $H h$), said rollers lying immediately below the aperture F^{11} in the folding-bed. The shaft G^5 , with the roller H , has its bearings in the bearing portions F^{15} of the depending brackets F^{12} , while the shaft g^5 is supported on the bearing portion h' of the arm H' , pivotally supported on the projecting arms F^{14} of the bracket F^{12} , as clearly shown in Fig. 28, a spring H^2 , secured to the bracket F^{12} , and the pivoted arm H' serving to draw the two rollers into contact with elastic pressure. The rolls $H h$, which turn freely on the shafts $G^5 g^5$, are connected to rotate in opposite directions by gear-wheels $H^3 h^3$ (see Fig. 31) and are driven through a pinion H^4 on the roller H by a gear-wheel H^5 , secured on the end of the shaft H^6 , supported on the bearing F^{13} of one of the brackets F^{12} , said shaft H^6 being also supported on one of the bearings F^6 , as shown in Fig. 24, and having attached near its outer end a spur-wheel H^7 and on its outer end a lever-arm H^8 , provided with a cam-roller h^8 . The shafts G^5 and g^5 are connected to rotate in opposite directions by the gear-wheels $G^6 g^6$ and are connected through the gear-wheel G^7 (see Figs. 24 and 28) by the shaft G^8 , having its bearings in F^{13} and F^6 , as shown in Fig. 24, and having secured to its outer end the lever G^9 , supporting the cam-rolls g^9 .

$I I$ (see Figs. 23, 24, 30, 32, &c.) are fingers, preferably having the triangular shape shown, pivoted together and also pivotally connected with slides I^3 , moving on the guides f^{10} in the apertures F^{10} , a portion of the slide extending through the aperture, as indicated at I^4 , and connecting with a slide-bar I^5 , moving in the guide-slot F^8 and having attached to its end a cam-roller i^5 . The slide or its depending portion I^4 has attached to it (see Figs. 24 and 32) a vertical perforated guide I^6 , slotted, as indicated at i^6 , and in which moves a rod I^7 , having pivoted to its upper end, as shown at I^8 , links I^9 , pivoted at their tops to

depending lugs I^{10} , attached to the folding fingers or plates I . The rod I^7 is perforated, and through it and the slot I^6 extends one end of a lever I^{11} , pivoted on the lugs F^5 and having a cam-roller I^{11} on its outer end. The distending-fingers I are thrown inward over the aperture F^{11} or withdrawn outward by the slide-rods I^5 , and they are folded together or spread apart by the action of the rock-lever I^{11} , acting on the rod.

$J J$ (see Figs. 23, 24, 25, 26, 27, 28, 29, and 32) are folding-plates having for their function the flattening of the box formed by the distending-plates $I I$ into the diamond fold and also the supplemental function of serving as guides for the folding over of the triangular flaps of the diamond in forming the bottom of the bag. They are preferably made broad at the base with narrower extensions bounded by parallel lines, as indicated at $j j$. As shown, the plates J are secured at their backs to castings J' , having at each end bearings $J^2 J^2$, by which they are pivotally connected to pivoted supporting-lugs J^3 , extending up from slides $J^4 J^4$, supported and moving in the slide-grooves $F^9 F^9$ at each end of the casting F' . The slides J^4 are connected at their rear ends with slide-rods $J^5 J^5$, supported in the slide-bearings F^{17} , and connected at their outer ends by a cross-bar J^6 , which cross-bar supports a cam-roller j^6 .

J^7 and j^7 indicate stops which regulate the extent of the movement of the slides J^4 .

The casting J' , to which the plate J is attached, has a lever-arm extension J^8 , (best shown in Fig. 32,) to which is pivotally connected the link J^9 , pivoted at its other end to a lug J^{10} , depending from the inner end of a slide-rod J^{11} , moving in the guide-slot F^{16} and having a cam-roller j^{11} at its outer end. As shown, a regulable amount of friction to hold the rod J^{11} in position is provided by means of a spring j^{12} , also inserted in the slot f^{16} , and regulated in pressure by a screw J^{12} . It will readily be seen that the plates $J J$ are given an inward-and-outward motion by the movement of the rods J^5 and a backward-and-forward folding motion by the movement of the slides J^{11} .

$K K$ (see Figs. 23, 25, 26, 27, and 28) are folding-plates supported on the brackets F^{18} on each side of the folding-bed through their depending lugs, (indicated at K' and K^2), the lugs K^2 being connected by links K^4 with fixed pivots K^6 , and the lugs K' being connected by links K^3 with a shaft K^5 , to which is attached a gear-wheel K^7 in engagement with a toothed segment K^8 , secured in turn to the shaft K^9 , which is supported in bearings F^{19} and has attached to its outer end the cam-contacting levers K^{10} and k^{10} . It will readily be seen that by oscillating the shafts K^9 the plates $K K$ will be moved from the position shown, for instance, in Fig. 28 to a position in which they will extend over the folding-bed, their movement being of a character which preserves in great measure their hori-

zontal position. The plates K K are drawn downward with elastic pressure by the action of the springs K¹¹ K¹¹, secured to the said plates and to the bracket-arms, (indicated 5 at K¹².)

The approximate position with reference to the stationary plates B² of the outer ends of the levers, slides, shafts, &c., which actuate the various folding devices above described, are shown in Fig. 16, and in Fig. 15 the position of the cams, &c., on the plates B² is indicated, those secured to the plates shown in the section being shown in full lines and those secured to the opposite plate being 15 shown in dotted lines, and in Figs. 33, 34, and 35 I have diagrammatically shown the cams, &c., secured to the two opposite plates B², which are here indicated as though they were straight bars, to which the cams, &c., 20 are secured. Referring specifically to these stationary actuating devices, L, Figs. 15 and 33, is a cam arranged to act upon the cam-roller h⁸ and through it to rotate the shaft H⁶ and give the take-in rollers H h a movement 25 for the take-in of the bag-blank.

L' is a cam arranged to act upon the cam-roller g⁹ and through it to actuate the shaft G⁸ and the defining-plates G G, causing them to close together and grip the bag on the line 30 of the main bottom fold.

L² L³ are cams situated opposite to each other on the bed-plates B² and arranged to engage and push in the cam-rolls i⁵ i⁵, which, acting on the slides I⁸ I⁸, thrust the folded 35 distending-fingers I I into the tucks of the projecting end of the bag-blank.

L³ L³ are oppositely-disposed cams secured on the plates B B and arranged to act upon the cam-rollers i¹¹ of the pivoted levers I¹¹ 40 and through said levers and the connections described to cause the fingers I I to move apart and spread out the end of the tube into a box form.

L⁴ L⁴ are oppositely-disposed cams situated 45 on the plates B² B² and arranged to act upon the cam-rollers j⁶ and through the slide-rods J⁵ and their described connections to thrust the folding-plates J J inward until they rest against or close to the upright ends of the 50 box.

L⁵ L⁵ are oppositely-disposed cams secured to the plates B² B², which act upon the cam-rollers j¹¹ and through the slides J¹¹ on the hinged folding-plates J J pressing them down 55 against the ends of the box-form and folding it into a diamond.

L⁶ L⁶ are oppositely-disposed cams arranged to act upon the cam-rollers i⁵ and through their connections to withdraw the 60 folding-plates I I from the triangular folds which they have assisted in making.

L⁷ L⁷ are oppositely-disposed cams arranged to act upon the cam-rollers j¹¹ and to partially retract the folding-plates J J, moving them to such an extent, as best shown in 65 Fig. 34, that the narrow portions with the

straight edges j j alone remain in contact with the diamond-folded blank.

L⁸ is a cam arranged to act upon the downwardly-extending wiper K¹⁰, secured to one of the shafts K⁹, and through said shafts to move one of the plates K inward, as shown at the right-hand side of Fig. 34, folding the flap of the diamond over upon the center of the diamond fold and over the straight edges 75 j j of the folder-plates J J.

L⁹ is a cam secured on the opposite plate B, both holding the cam L⁸ and arranged to act upon the wiper-arm k¹⁰ of the other shaft K⁹ and through said shaft to move the second folding-plate K inward, as shown at the left-hand side of Fig. 35, so as to complete the folding of the diamond into a bag-body. 80

L¹⁰ L¹⁰ are oppositely-disposed cams arranged to act upon the cam-roller j⁶ and through them to completely retract the plates J J. 85

L¹¹ is a cam arranged to act upon the wiper-arm k¹⁰ of the first shaft K⁹, so as to retract the folding-plate K, to which it is attached. 90 L¹² is a similar cam secured on the opposite side of the machine, arranged to act upon the wiper K¹⁰ of the second shaft K⁹, so as to retract the second folding-plate K.

L¹³ is a cam arranged to act upon the cam-roller g⁹ and through the shaft G⁸ to move the defining-plates G G back to their position. 95

L¹⁴ is a stationary rack secured to one of the plates B² in position to engage the spur-wheel H' on the shaft H⁶ and by said engagement to rotate said shaft in the opposite direction to that in which it is rotated by the cam L, so as to eject the tube. 100

L¹⁵ L¹⁵, Fig. 33, are oppositely-disposed cams arranged to act upon the cam-rollers j¹¹ and through the slides J¹¹ to rotate the folding-plates j j to their upright position. 105

L¹⁶ L¹⁶ are oppositely-disposed cams arranged to act upon the cam-roller i¹¹ and through the pivoted levers I¹¹ to close the distending plates or fingers I I together. 110

L¹⁷ is a cam arranged to act upon the cam-roller h⁸ and through it and the shaft H⁶ on the take-in rolls H h, so as to bring them to the exact position they should occupy prior 115 to the engagement of the cam-roller h⁸ by the cam L.

In Figs 47, 48, and 49 I have shown a slight modification in the construction of the distending plates or fingers I I, the ends of the 120 plates being cut off and each plate being provided with pivoted supporting-lugs M, to which are secured pivotally-supported gripping-fingers M', pressed inward against the face of the plate by springs M². Each plate I is also provided with a projecting pin M³ and with a perforation M⁴, through which the pin on the other hinge-plate projects when the plates I I are folded together, as shown in Fig. 48. In this position the pins M³ press against the fingers M', pushing them outward, so as to 125 permit the folded edges of the bag-blank to 130

pass between each plate I and its finger M', so as to be engaged by the spring-plate M² when the plates I I are folded outward.

In Figs. 36 to 40, inclusive, I have shown a supplemental device which I have used in connection with my machine and as a part of it, having for its function a more accurate defining of the box into which the end of the tube is spread, as shown in Fig. 41, prior to the operation of folding it into a diamond and completing the bag-bottom. In these figures N N' represent the framing of the device secured on the plates B², the framing N on one side supporting the shaft n², to which is attached a gear-wheel N³ in engagement with a gear-wheel C' and a gear-wheel N⁴, driving an intermediate gear-wheel N⁵, secured on the shaft N⁶, to which shaft is secured the sprocket-wheel N⁷, a similar sprocket n⁷ being secured on a shaft n⁸, supported on the framing N'. N⁸, N⁹, N¹⁰, N¹¹, and N¹² are cams secured on the framing, as best shown in Fig. 36. N¹³ is a chain-wheel moving on the sprocket-wheels and having attached to it at regular intervals the box-distending device, (indicated at O O, &c.,) the framing of which has attached to its opposite sides trunnions O' O', to which the chains are attached. The box-like castings O are of hollow rectangular internal form crossed by a web having a roll-bearing, as shown at O², and having at the sides projecting flanges O³. Pivoted to the lower edges of the casting O are the distending-plates O⁴ O⁴ O⁵ O⁵, pressed inward by springs O⁶ and resting against a wedge-like plunger (indicated at O⁷) moving in the rectangular opening in the casting O and attached to a rod O⁸, which passes through the bearing O⁹ and has a cam-roll O⁸ attached to its upper end. When the plunger O⁷ is moved downward, the plates O⁴ and O⁵ are moved outward to the position shown in dotted lines in Figs. 39 and 40. The chains move in the direction indicated by the arrow in Fig. 36, and for a portion of their movement the distenders move substantially in lines with the folding-beds, being guided by the cam-plates N¹¹; but before coming under the action of these cam-plates the distending-plates O⁴ O⁵ are thrust into the mouth of the box formed at the end of the tube on the folding-bed, the plunger O⁷ being at this time retracted by the action of the cam N⁹. Then after the box has come under the action of the segmental cam N¹¹ the plunger is acted on by the cam N¹², forcing the plates O⁴ and O⁵ outward and fully distending the box at the end of the tube, after which the plunger is withdrawn by the action of the cam N¹⁰, and the distending device then leaves the box and, moving up over the sprocket-wheel, returns to engage with another box, the plungers being held in position during their backward movement by the cam N⁸.

65 In Fig. 14 of the drawings I have a device for applying paste to the diamond fold prior to the completion of the bottom folding, and,

referring to this figure, P indicates a gear-wheel driven by the gear-wheel C' and having attached to its shaft a second gear-wheel P', which through an intermediate gear P² drives a gear-wheel P³, secured to a shaft P⁹, on which is also secured a gear-wheel P⁴, driving a gear-wheel P⁵, which directly drives a paste-roller P⁷, running in a paste-trough P⁸ and so as to apply paste to the segmental pasting-rollers P⁶ P⁶, secured on the shaft P⁹.

It is sometimes desirable to provide means for opening the mouth of the bag-blank prior to the entrance of the distending-fingers I I, and in Figs. 42 to 46 I have shown such a device as driven by the shaft P⁹, to which are also attached the pasting-segments, P¹⁰ indicating a sprocket-wheel secured on said shaft and communicating motion through a chain-wheel P¹¹ to a sprocket-wheel P¹², driving a shaft P¹³, having bearings in sleeves p¹³ p¹³, extending from the opposite plates B² and ending in those plates (indicated at P¹⁴) secured on the shaft P¹³. Between the plates P¹⁴ is a bearing p¹⁵, supporting a rod P¹⁶, having at its end a thin distending-plate P¹⁷ and also projecting fingers, (indicated at P¹⁸,) which as the rod P¹⁶ revolves with shaft P¹³ come in contact with fingers P¹⁵ on the face-plate P¹⁴ and cause the shaft or rod P¹⁶ to revolve. The arrangement of the parts is such that the distending-plate P¹⁷ enters the mouth of the tube, as shown in Fig. 45, and, revolving with the tube for a short distance, revolves also on its own axis, spreading the mouth of the tube, as shown in Fig. 46, at the time when the holders I I enter it. I have also shown in Figs. 42 and 43 a presser-segment (indicated at P²³) attached to a roll P²² and driven by a shaft P²¹, having at its end a sprocket-wheel P²⁰, driven through a chain-wheel P¹⁹ by a sprocket-wheel on the shaft P⁹.

In Fig. 14 I have indicated a device for receiving and delivering the bags as they are ejected from the folding-beds. As shown, this consists of a series of rolls or drums (indicated at Q', Q², Q³, Q⁴, Q⁵, and Q⁶) over which runs the belt, (shown at Q⁷.) The rolls H h eject the completed bag immediately above the portion of the belt Q⁷ which lies between the guide-rolls Q⁶ and Q', so that the bottom of the bag occupying the position with respect to the body indicated in Fig. 12 impinges directly upon the belt and is carried forward between the rolls Q' and Q, where it is engaged by both belts and the bag with the bottom bent over upon the body, as indicated in Fig. 13, carried around the roller Q, and finally ejected between the rolls Q⁴ and Q⁵.

In Fig. 50 I have shown a modification of my machine in which the folding-beds instead of being attached to the periphery of disks E E are supported on chains, as indicated at R³, said chains being returned and actuated by sprocket-wheels supported on the shafts R' R', which have their bearings in the frame (indicated at R) and support the guide R², which keeps the chain level at the top.

In this figure, R⁴ indicates the main driving-wheel extending to the wheel C', and the rest of the parts making up the machine are so nearly identical with those already described that it is unnecessary to refer specifically to them.

The operation of the machine is simple and has been already indicated sufficiently. To briefly indicate the operation of the machine at this point, the blanks are fed to the machine by the rolls D' D² passing the rolls D³ and D⁴ and being directed and guided into the apertures F¹¹ and between the defining-plates G G by the action of the directing-finger D⁸, as best indicated in Figs. 18 to 22. At the time when the end of the tubular blank is engaged by the drawing-in rolls H h (see Fig. 20) it is also engaged by the segment d³ d⁴ of the rolls D³ D⁴ and straightened out, and then when the rolls H h have drawn in the tube for the determined distance (regulated by the conformation of the cam L) the defining-fingers G G move in under the influence of the cam L', grip the tubular blank on the lines upon which the bottom is to be opened and spread its free end somewhat, as indicated in Fig. 32. After the plates G have engaged the blank the next instrumentality to act upon it is the distending-plate P¹⁷, if such a plate is used, which opens the mouth of the bag, as shown in Figs. 45 and 46. Then the distending-fingers I I, folded together, are caused to move into the side tucks of the bag by the action of the cams L² L³, and then the distending-fingers are caused to move apart by the action of the cams L³, opening up the bottom of the bag into a box form. The next operation performed is that of the folding-plates J, which are caused to move inward toward the sides of the blank and to fall downward against these sides by the action of the cams L⁴ and L⁵, and the folder-plates I I are withdrawn by the action of the cams L⁶, and next in my preferred construction the plates J are partially withdrawn, so as to leave only their narrowed straight-edged portions j projecting over the diamond fold. Next in order the paste is applied to the diamond fold, and then the folding-plates K K are acted on by the cams L⁸ and L⁹, folding the flaps of the diamond fold over and completing the bottom of the bag. The plates J are then entirely retracted by the action of the cams L¹¹ L¹², after which the pasted bottom of the bag may very properly be pressed down by the action of the presser P²³, and then the drawing-in rolls H h are reversed by the action of the rack L¹⁴, ejecting the bag from the folding-bed, the other cams, already described, returning the various folding devices to their initial position to enable the bed and its coacting devices to act again, as described, upon another blank.

Having now described my invention, what I claim as new, and desire to secure by Letters Patent, is—

1. In a paper-bag machine comprising a car-

rier and a series of folding-beds secured to and moving with said carrier, the combination with said carrier and folding-beds of 70 blank-feeding mechanism arranged to deliver the blanks at an angle to the beds and a moving deflector arranged to guide the blanks onto the moving beds.

2. In a paper-bag machine a folding-bed 75 having an aperture to receive and hold the body of a blank at an angle to the face of the bed in combination with take-in mechanism for engaging and drawing into the aperture a determined length of the blank and reversing devices whereby the tube is ejected after the bag-bottom is folded.

3. In a paper-bag machine a folding-bed having an aperture to receive and hold the body of a blank at an angle to the face of the 85 bed in combination with take-in rolls moving with the folding-bed for engaging and drawing into the aperture a determined length of the blank.

4. In a paper-bag machine a folding-bed 90 having an aperture to receive and hold the body of a blank at an angle to the face of the bed in combination with take-in rolls for engaging and drawing into the aperture a determined length of the blank and mechanism for reversing the take-in rolls to eject the bag after its bottom is folded.

5. In a paper-bag machine, a moving carrier having attached to it a series of folding-beds, each having an aperture to receive and hold the body of the bag-blank at an angle to the face of the bed in combination with take-in mechanism arranged to draw into and eject from the aperture the body of the blank, and bottom-folding mechanism moving with 100 each bed for spreading out the end of the bag-blank into a diamond fold on the face of the beds.

6. In a paper-bag machine, a moving carrier having attached to it a series of moving 110 folding-beds, each having an aperture to receive and hold the body of the bag-blank at an angle to the face of the bed in combination with take-in mechanism arranged to draw into and eject from the aperture the body of the blank, and bottom-folding mechanism moving with 115 each bed for spreading out the end of the bag-blank into a diamond fold on the face of the beds and folding in the ends of the diamond also on the bed-face.

7. In a paper-bag machine, a rotatively-moving carrier having attached to it a series of moving folding-beds, each having an aperture to receive and hold the body of the bag-blank at an angle to the face of the bed in 125 combination with take-in mechanism arranged to draw into and eject from the aperture the body of the blank, bottom-folding mechanism moving with each bed for spreading out the end of the bag-blank into a diamond fold on the face of the beds and folding in the ends of the diamond also on the bed-face and a progressively-arranged series 130 of stationary cams arranged to engage and

operate the mechanism of each bed successively.

8. In a paper-bag machine, a rotating carrier having a series of folding-beds secured to it, each bed having in combination therewith a fold-defining mechanism for holding a blank tube on the line on which the bottom is opened, distending-fingers for entering and spreading out the bottom of the tube into a box form, folding-plates for pressing the box into a diamond form and flap-folding plates for folding the ends of the diamond into a complete bag-bottom, said mechanism having also secured to its stationary parts a series of actuating devices arranged to act successively on the folding devices as the beds successively pass the same points.

9. In a paper-bag machine, a rotating carrier having a series of folding-beds secured to it, said beds having apertures to receive and hold the body of a tubular bag-blank at an angle to the face of the folding-bed, each bed having in combination therewith a pair of fold-defining plates pivoted in the aperture and arranged to grip a blank tube on the line on which the bottom is opened, distending-fingers for entering and spreading out the bottom of the tube into a box form, folding-plates for pressing the box into a diamond form and flap-folding plates for folding the ends of the diamond into a complete bag-bottom, said machine having also secured to its stationary parts a series of actuating devices arranged to act successively on the folding devices as the beds successively pass the same points.

10. In a paper-bag machine, a rotating carrier having a series of folding-beds secured to it, said beds having apertures to receive and hold the body of a tubular bag-blank at an angle to the face of the folding-bed, each bed having in combination therewith a pair of fold-defining plates pivoted in the aperture and arranged to grip a blank tube on the line on which the bottom is opened, a pair of drawing-in rolls arranged beneath the aperture and adapted to draw in a determined part of a blank tube and afterward to eject the same, distending-fingers for entering and spreading out the bottom of the tube into a box form, folding-plates for pressing the box into a diamond form and flap-folding plates for folding the ends of the diamond into a complete bag-bottom, said machine having also secured to its stationary parts a series of actuating devices arranged to act successively on the folding devices as the beds successively pass the same points.

11. In combination with a folding-bed and means for spreading out the ends of a tucked tube into a box form thereon, a pair of sliding and folding plates, as J, having straight edges *j* arranged to fold the box into a diamond fold, means for actuating said plates first to fold down the box into the diamond, flap-folding devices arranged to fold in the end flaps of the diamond over the straight

edges of the plates J and means for retracting all the folding devices after the bag-bottom is formed.

12. In combination with a folding-bed and means for spreading out the end of a tucked tube into a box form thereon, a pair of sliding and folding plates, as J, having straight edges *j* arranged to fold the box into a diamond fold, means for actuating said plates first to fold down the box into the diamond and then to partially retract the plates so that only their straight-edged portions rest on the blank, flap-folding devices arranged to fold in the end flaps of the diamond over the straight edges of the plates J and means for retracting all the folding devices after the bag-bottom is formed.

13. In a paper-bag machine having a rotating carrier and a series of folding-beds secured thereto, said folding-beds being formed with apertures to receive and hold the body of a tucked tubular blank at an angle to the face of the bed, the combination with each bed of hinged plates in the aperture adapted to engage and define the bottom-fold line, box-distenders adapted to spread the end of the blank into box form, sliding and folding plates, as J, adapted to fold the box into a diamond said plates having straight edges, as *j*, flap-folders adapted to fold in the end flap of the diamond over the edges *j* of the plates J and means for operating said folding devices secured to a stationary part of the machine and acting thereon successively.

14. In a paper-bag machine, the combination with a traveling folding-bed having mechanism for spreading the end of a tucked tubular blank into a box form adapted to enter and operate on the tucks of the blank, of a tuck-spreader, consisting of a thin plate, mechanism for moving the plate to enter the mouth of the bag before the tuck-spreading mechanism enters the tucks and remain in it while the spreading mechanism is entering the tucks and mechanism for turning the thin plate to spread the mouth and tucks of the tube end.

15. In a paper-bag machine having a revolving carrier and a series of folding-beds moving therewith, means for gripping tucked tubular blanks to and spreading out their ends upon the beds comprising spreading-fingers adapted to enter and act upon the tucks, a rotating blade arranged to enter the end of each tube at a point in the travel of the bed before the spreading-fingers enter the tucks and to remain in the tube end while the spreaders enter the tucks and means for revolving said blade to spread the tube end and tucks.

16. In a paper-bag machine having a revolving carrier and a series of folding-beds moving therewith and provided with mechanism for spreading the end of a tubular blank into a box form thereon and afterward folding said box into a bag-bottom, the combination of a series of box-distenders moving in the same direction as the folding-beds during

- a portion of their movement and arranged to temporarily enter and distend the box-like ends of the tube after they have been opened by the mechanism connected with the beds.
- 5 17. In a paper-bag machine having a revolving carrier and a series of folding-beds moving therewith and provided with mechanism for spreading the end of a tubular blank into a box form thereon and afterward folding said box into a bag-bottom, the combination of a series of expandible box-distenders

moving in the same direction as the folding-beds during a portion of their movement and arranged to temporarily enter and expand to distend the box-like ends of the tube after 15 they have been opened by the mechanism connected with the beds.
